UNITED STATES PATENT OFFICE.

EMIL ZULLIG, OF WEEHAWKEN, NEW JERSEY.

DESIGN FOR LACE.

51,745.

Specification for Design.

Patented Feb. 5, 1918.

Application filed December 1, 1917. Serial No. 204,989. Term of patent 3½ years.

To all whom it may concern:

Be it known that I, EMIL ZULLIG, a citizen of the Republic of Switzerland, residing at 208 Dodd street, Weehawken, county of Hudson, and State of New Jersey, have invented a new, original, and ornamental Design for Lace, of which the following is a specification, reference being had to the accompanying drawing, forming part thereof.

The figure is a plan view of a piece of lace showing my new design.

I claim,

The ornamental design for lace as shown.

EMIL ZULLIG.
